Attorney, Agent, or Firm—Connolly Bove Lodge & Hutz LLP

[57] **CLAIM**

The ornamental design for a mattress overlay, as shown and described.

DESCRIPTION

FIG. 1 is a top plan view of a mattress overlay showing the top surface of our new design;

FIG. 2 is a right side elevational view of our design, with the left side elevational view being identical thereto;

FIG. 3 is a front elevational view of the mattress overlay in partial cross-section taken along line 3—3 of FIG. 1, with the rear end elevational view being identical thereto;

FIG. 4 is a cross-sectional view taken along line 4—4 of FIG. 1; and,

FIG. 5 is a bottom plan view of the mattress overlay.

1 Claim, 1 Drawing Sheet Fig. 2.

Fig. 3.

Fig. 4.

Fig. 5.
